UNITED STATES PATENT OFFICE

WILLIAM KELSO, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA

CAR COUPLER

Application filed December 29, 1924. Serial No. 758,702.

My invention relates to car couplers and is especially applicable to the form known as the standard D-type coupler, although it is to be understood that the improvements are 5 applicable to Master Car Builders' couplers of other types.

The principal object of the invention is to provide lock operating means serving efficiently to prevent accidental unlocking of 10 the lock when the coupler is in service. A further object of the invention is to produce a lock actuating device affording a plurality of means for locking the lock in locked position; and a still further object is to provide a lock-to-the-lock mechanism which is 15 of simple form and capable of being readily assembled with the parts with which it is associated.

The primary feature of the invention, generally stated, consists in the employment, 20 in combination with a coupler head, a rotatable knuckle, and a lock for said knuckle, of means for moving the lock to unlocked position, the said means being movable with 25 respect to the lock and involving a plurality of relatively movable members, each of the members being capable of engaging the coupler head to prevent accidental unlocking 30 of the lock, and one of said members being adapted thus to engage the head when the other of said members occupies a position 35 permitting unlocking of the lock.

Another feature of the invention consists 35 in combining with a coupler head, a rotatable knuckle and a lock for said knuckle, mechanism actuating the lock to cause it to assume unlocked position, the said mechanism being movably connected to the lock and involving two members connected by a joint 40 permitting their relative rotation, the said mechanism being capable of cooperating with the coupler head to provide successively operating means for preventing accidental unlocking of the lock, and means being provided whereby the said joint is constrained to break only in a direction suitable for permitting the parts of the lock actuating mechanism to return to locked relation with the lock when the latter is in its locked position.

50 Other features of the invention residing in

advantageous details of construction and in special relations of parts will hereinafter appear.

In the drawings illustrating the invention applied to a Master Car Builders' standard 55 D-coupler,—

Figure 1 is a vertical sectional view of mechanism embodying the invention, the lock for the knuckle and the device for actuating the lock being shown in elevation and in 60 locked relation.

Figure 2 is a vertical sectional view similar to Fig. 1 but illustrating a relation of the parts in which the upper or supplemental lock-to-the-lock is in its effective position. 65

Figure 3 is a vertical sectional view illustrating a position assumed by the parts when the lock is actuated to throw the knuckle open.

Figure 4 is a detail view in side elevation 70 of the lock actuating mechanism as viewed from the guard arm side of the coupler, the connected members of the device being in the position illustrated in Fig. 3.

Figure 5 is a detail rear elevational view 75 of the lock actuating device.

Figure 6 is a detail sectional view on the line 6—6, Fig. 3.

Figure 7 is a view corresponding to Fig. 2 but illustrating a modified form of the invention. 80

Figures 8 and 9 are detail views, in rear and side elevation, respectively, of the modified form of lock controlling mechanism shown in Fig. 7, the parts thereof being in 85 the positions they assume when the lock is being raised to unlocked position.

Figure 10 is a detail sectional view on the line 10—10, Fig. 9.

As is well known, the rotatable knuckle of the D-coupler is normally prevented from executing an uncoupling rotation by means of an upwardly movable and rearwardly swinging lock. When applied to freight cars this lock is usually associated with a lock lifter whose upper end projects through an opening in the top wall of the coupler head and whose lower end is formed with oppositely extending trunnions which project into an upwardly and rearwardly opening slot in 90 95 100

the lock so as to connect these two parts in a manner permitting them to have relative sliding and rotating movements. This common form of top operating lifter for the D-coupler lock is a single rigid member whose 5 lower end, when the parts are in locked relation, projects rearwardly beyond the lock so as to extend beneath an anticeep lug or shoulder upon the interior of the coupler head and thereby 10 constitute means for preventing accidental unlocking of the lock. It will be perceived that if, as a result of the jarring to which the coupler is subjected when the car is in motion, or through any other cause, the 15 lower end of the standard top-operating lifter fails to perform its lock-to-the-lock function, instances of which have been known to occur, the lock becomes free to execute an accidental unlocking movement permitting 20 the knuckle to swing outwardly to uncoupled position. By the employment of a jointed lock lifter embodying my invention, however, the same lock-to-the-lock feature now present in the standard D lifter is preserved, and supplemental or auxiliary means 25 are provided for positively arresting an unlocking movement of the lock in the event that the means intended to perform that function initially should fail to operate.

30 In the drawings, 1 indicates the coupler head upon which the knuckle (not shown) is rotatably mounted in the customary manner. Outward rotation of the knuckle to uncoupled position is normally restrained by a 35 vertically sliding and rearwardly swinging gravity actuated lock 2 having a depending leg 3 which projects downwardly through an opening 4 in the lower wall of the coupler head when the parts are in locked relation. When the lock is caused to execute an extended 40 unlocking movement it swings rearwardly, as shown in Fig. 3, causing its depending leg to operate the pivoted knuckle opener 5 and thus effect uncoupling rotation of the 45 knuckle.

50 The lock 2 may be and preferably is of the usual design, that is to say, it is provided with an upwardly and rearwardly opening slot 6 for receiving the lower end of the lock actuating device, the bottom of the said slot being inclined downwardly toward the rear of the coupler so that under the influence of gravity the lower end or shoulder 7 of the lifting mechanism may be caused to protrude through the slot and normally assume a 55 position beneath the anticeep shoulder or lugs on the interior of the coupler head. The side walls of the slot are provided with the usual pockets or recesses 9 for receiving the oppositely extending trunnions 10 whereby the lock and its lifting device are slidably and rotatably connected.

60 The lock 2 is actuated by means of a jointed lifter device involving two members, the lower one being slidably and rotatably con-

nected to the lock, and the upper one extending through an opening 11 in the top wall of the coupler head. The upper member may advantageously be provided with an aperture 12 affording means for attaching a suitable uncoupling lever or release rigging, and it preferably is formed with a rearwardly extending lug or shoulder 13 which normally stands in overlapping relation to the upper wall of the coupler head when the lock 2 and its actuating means are in locked relation.

65 In the construction shown in Figs. 1 to 6, inclusive, the upper member 14 is pivotally connected to the lower member 15 by means of a rivet 16 passing through the two members, the upper member being forked or bifurcated at its lower end, as indicated at 17, (see Fig. 5) to receive the tongue 18 with which the upper end of the lower member is provided. To prevent this hinged joint from breaking in a direction rearward of the coupler when the parts are returning to normal locked relation after an unlocking movement of the lock 2, the bifurcated lower end of the upper lock lifting member 14 is preferably extended below the pivot 16 so as to provide lugs or shoulders 19 adapted to engage cooperating lugs 20 on the member 15 to thereby limit the rotation of lifting members 14 and 15 with respect to each other. The lower portion of the lifter member 15 preferably is the same in form as the corresponding part of the top-operating D-coupler lifter commonly employed and it cooperates with the coupler head in the usual well known manner.

70 The forward side of the upper member 14 of the lock actuating mechanism is provided above the pivot 16 with a portion 21 constituting a face or shoulder which normally stands beneath and in overlapping relation with the top wall 22 of the coupler head adjacent the opening 11 in the latter. As shown this portion 21 of the lifter member 14 is preferably rounded in the form of a hump. As will be readily understood from a consideration of the positions of the lock lifting mechanism illustrated in Figs. 1 and 2, the lock 2 is normally locked in locked position by the cooperation of the lower end or shoulder 7 of the lifting member 15 with the anticeep lug 8 of the coupler head beneath which it projects. If, as shown in Fig. 2, the member 15 should move upwardly with respect to the coupler lock so as to withdraw the lower end 7 of said lifter member from beneath the lock-down shoulder 8, the engagement of the face or shoulder 21 of the upper lifter member 14 with the inside surface of the top wall 22 of the coupler head will arrest the accidental movement of the lock 2 before it has proceeded to any substantial extent. On pulling upwardly upon the lifter mechanism to effect an unlocking movement of the lock, the mem- 75 80 85 90 95 100 105 110 115 120 125

bers 14 and 15 of said mechanism rotate with respect to each other on their pivotal connection 16 so as to withdraw the locking shoulder 21 from beneath the upper wall of the 5 coupler head and permit it to pass out through the opening 11 in said wall. The initial upward movement of the lifter device with respect to the lock 2 causes the lower end 7 of the lifter member 15 to be retracted into the slot 6 of the lock and a continued pull upwardly 10 upon the member 14 of the lifting device will effect an extended unlocking movement of the lock, as shown in Fig. 3. When the knuckle is closed and the lock falls to locked 15 position the jointed lock lifting mechanism is restored to normal locked position as illustrated in Fig. 1, such action being induced by gravity.

The modified form of the invention shown 20 in Figs. 7 to 10, inclusive, substantially differs from the construction heretofore described only in respect to the means for limiting the relative rotation of the upper and lower members of the jointed lock lifting mechanism. Instead of forming the upper lifter member 24 with a shoulder 19 for cooperating with a lug or shoulder 20 on the lower lifter member 25, as is the case in the structure illustrated in the principal figures 25 of the drawings, relative rotation of the 30 lifter members 24 and 25 is limited by providing the latter with a slot 26 through which extends a rivet 27 passing through the bifurcated end of the lifter member 24. The members 24 and 25 otherwise correspond in form 35 and function to similar parts heretofore described and accordingly have been identified by corresponding reference characters.

While the specific details of construction 40 illustrated in the drawings are regarded as preferable it will be understood of course that variations in details of construction may be made without departing from the spirit and scope of the invention.

45 I claim:—

1. In a car coupler, the combination with a coupler head, a rotatable knuckle, and a vertically movable lock for said knuckle, of means for actuating said lock to cause it to assume unlocked position, said means being movably connected to said lock and involving a plurality of connected members which are movable with respect to said head and said lock and also with respect to each other, each 55 of said members being adapted to engage said head to prevent accidental unlocking of said lock, and one of said members being adapted to engage said head to prevent accidental unlocking of said lock when the other of said 60 members is in a position permitting unlocking of said lock.

2. In a car coupler, the combination with a coupler head, a rotatable knuckle, and a vertically movable lock for said knuckle, of 65 means for actuating said lock to cause it to

assume unlocked position, said means being slidably and rotatably connected to said lock and involving a plurality of rotatably connected members each of which is adapted to engage said head to prevent accidental unlocking of said lock, one of said members being adapted to engage said head to prevent accidental unlocking of said lock when the other of said members is in a position permitting unlocking of said lock, and said members 70 when actuated to move said lock to unlocked position being adapted to move with respect to said lock and to rotate with respect to each other so as to free said lock for extended unlocking movement. 75

3. In a car coupler, the combination with a coupler head, a rotatable knuckle, and a vertically movable lock for said knuckle, of means for actuating said lock to cause it to assume unlocked position, said means being movably connected to said lock and involving a plurality of movably connected members each of which is adapted to engage said head to prevent accidental unlocking of said lock, accidental movement of one of said connected members to a position in which it is inoperative to prevent unlocking of said lock serving to move the other of said members towards its position for restraining unlocking of said lock. 95

4. In a car coupler, the combination with a coupler head, a rotatable knuckle, and a gravity actuated lock for said knuckle, of means for actuating said lock to cause it to assume unlocked position, said means being movably connected to said lock and involving a plurality of movably connected relatively rotatable members provided with cooperating means for limiting their relative rotation, each of said members being adapted to engage said head to prevent accidental unlocking of said lock, and one of said members being adapted to engage said head to prevent accidental unlocking of said lock when the other of said members is in a position permitting unlocking of said lock. 100

5. In a car coupler, the combination with a coupler head, a rotatable knuckle, and a lock for said knuckle, of mechanism for actuating said lock to cause it to assume unlocked position, said mechanism being movably connected to said lock and involving two members having a jointed connection permitting them to rotate with respect to each other, said mechanism being cooperable with said head at a plurality of points to provide a plurality of successively operating means for preventing said lock from accidentally moving to unlocked position, and said lock actuating mechanism being provided with means whereby said joint is permitted to break only in the direction necessary to allow said mechanism to return to locked relation with said lock when the latter is in locked position. 115

6. In a car coupler, the combination with 120

4

a coupler head, a rotatable knuckle, and a vertically movable lock for said knuckle, of means for actuating said lock to cause it to assume unlocked position, said means involving a plurality of members connected to each other with capability of relative rotation, one of said members being slidably and rotatably connected to said lock and being adapted to engage said head to prevent accidental unlocking of said lock, and another of said members having its upper end projecting above the upper wall of the coupler head and being formed above said head with a shoulder adapted to stand in overlapping relation to said wall when said lock and its actuating means are in normal locked relation.

7. In a car coupler, the combination with a coupler head, a rotatable knuckle, and a lock for said knuckle, of means for actuating said lock to cause it to assume unlocked position, said lock being provided with a slot adapted to receive said means, said means involving upper and lower members jointedly connected so as to be capable of rotation with respect to each other and to said lock, said lower member being provided with trunnions received by said slot and cooperating with said lock to operatively connect said lock and said means and adapted at its lower end to extend under a portion of said head to prevent accidental unlocking of said lock, and said upper member being adapted to extend under a portion of said head above said lock to prevent accidental unlocking of the latter.

8. In a car coupler, the combination with a coupler head, a rotatable knuckle, and a lock for said knuckle, of means for actuating said lock to cause it to assume unlocked position, said means and said lock being operatively connected so as to be capable of sliding and rotating with respect to each other, said lock being provided with a slot which opens through the top and one of the sides of said lock, said means involving upper and lower members movably connected so as to be capable of rotating with respect to each other, said lower member being provided with trunnions permitting it to slide and rotate with respect to said lock, said trunnions engaging said lock within said slot, said lower member having a portion adapted to project beyond said lock and under a portion of said head to prevent accidental unlocking of said lock, and said upper member being adapted to extend under a portion of said head to prevent accidental unlocking of said lock.

9. In a car coupler, the combination with a coupler head, a rotatable knuckle, and a lock for said knuckle, of means for actuating said lock to cause it to assume unlocked position, said means being slidably and rotatably connected to said lock and being adapted to assume a plurality of positions in each of which

said lock is thereby prevented from accidentally unlocking, each of said positions of said means enabling the latter to cooperate with a different portion of said head to prevent accidental unlocking of said lock.

70
In testimony whereof I affix my signature.
WILLIAM KELSO.
